UNITED STATES PATENT OFFICE.

JOHN R. GAMMETER, OF AKRON, OHIO, ASSIGNOR TO THE B. F. GOODRICH COMPANY,
OF NEW YORK, N. Y., A CORPORATION OF NEW YORK.

INTERNAL-PRESSURE VULCANIZING APPARATUS.

Application filed February 13, 1922. Serial No. 536,078.

To all whom it may concern:

Be it known that I, JOHN R. GAMMETER, a citizen of the United States, residing at Akron, in the county of Summit and State 5 of Ohio, have invented a certain new and useful Internal-Pressure Vulcanizing Apparatus, of which the following is a specification.

This invention relates to apparatus for 10 vulcanizing hollow rubber articles under internal fluid pressure, and more particularly to vulcanizers for annular tubes. One of my objects is to facilitate the connection and disconnection of a steam or other pressure 15 sure supply pipe with a conduit on the mold leading to the interior of the inflatable article therein, and a further object is to facilitate the quick placing, in fluid-tight connection with a conduit-section permanently 20 located on the mold, of a detachable discharge section of said conduit, which discharge section may include a discharge member such as the inflating-valve stem or casing for the tube, located tangentially within 25 the latter, or any other type of discharge member leading to the mold cavity.

Of the accompanying drawings:

Fig. 1 is a plan view, with parts broken away and in section, of a hot-plate press 30 platen and apparatus thereon embodying a preferred form of my invention.

Fig. 2 is a section on line 2—2 of Fig. 1 showing also the upper platen of the press.

Referring to the drawings, 10 is the lower 35 and 11 is the upper platen of a press, said platens being formed with the usual steam passages 12 and 13 respectively (Fig. 2). 12^a, 13^a are steam supply and discharge pipes for the lower platen and similar ones (not 40 shown) are provided for the upper platen. 14 is the lower and 15 the upper section of a two-part annular mold, and 16 is a rubber inner tube therein. 17 is a block-like fluid coupling member screw-bolted to the inner 45 periphery of the lower mold section and formed with a chamber 18, below which is a socket 18^a communicating with a pipe 19 which traverses the lower mold member 14 to the outer periphery of the latter, said 50 pipe lying in a groove on the under side of said member. 20 is an annular, conical lip-packing member, preferably of soft rubber, mounted in the wall of said socket and adapted to receive and form a fluid seal

against the outer wall of a downwardly-tapered, apertured plug 21, the aperture of which, 22, communicates with the lower region of the socket and with a horizontal pipe 23 non-rotatably mounted in the upper part of said plug and extending into the interior of the inner tube 16 within the mold cavity, passing through the valve-stem hole in the wall of the tube.

From the upper portion of the plug 21 to the wall of the mold cavity the pipe 23 is 65 surrounded by, a tight-fitting collar 24, which may be integral with the plug 21 or otherwise secured against turning on the pipe 23, and which is formed with a concave end surface 25 constituting, about the 70 pipe 23, a part of the wall of the molding cavity. The end of the pipe 23 extending from the opposite side of the plug 21 is closed by a plug 26 and is provided with a handle 27. The lower mold-section 14 and 75 the block 17 are grooved to accommodate the collar 25 and the pipe 23, as will be clearly seen by reference to Fig. 2, and the upper mold section 15 and a block 28 screw-bolted to the inner periphery thereof opposite the 80 block 17 are likewise grooved and adapted to fit closely over said collar and pipe.

The end portion, 29, of the pipe 23 lying within the mold cavity is bent so that its extremity lies substantially in a tangential position at the center of said cavity, and said extremity is provided with a female-threaded member 30 into which is screwed an inner-tube valve-stem or casing 31, the latter thus being adapted to receive steam from the 85 pipe 23 and discharge it tangentially into the cavity within the tube 16.

The plug 21, pipe 23, collar 24 and handle 27, as here shown, constitute a steam-conducting structure adapted to be detachably 95 seated in one of the mold sections and to be lifted therefrom with the work when the latter is removed from the mold.

For connecting the mold-traversing pipe 99 with a steam supply-line I preferably provide, as shown, a fluid-coupling member 32 screw-bolted to the outer periphery of the lower mold section and formed with a socket 33, the inner end of which communicates with the pipe 19, said socket being provided 105 with an annular, conical lip-packing member 34, preferably of soft rubber, adapted to receive and form a fluid seal against the

outer surface of one tapered end of an aperture plug 35, the other end of said plug being taper-threaded into the through passage of a coupling block 36 secured on the lower 5 press platen 10. 37 is an apertured plug taper-threaded into the opposite end of said coupling block, said plug 37 being mounted on the end of a flexible hose 38 leading from a steam line.

10 The sockets 18^a and 33, for the plugs 21 and 35, respectively, preferably are formed, as shown, with metal seating surfaces for the plugs at both ends of the lip-packing in order to assure a proper seating of the plug 15 and relieve the packings of undue pressures and consequent wear.

In the operation of the apparatus the inner tube 16 is formed and assembled with its valve stem 31 and the steam-conducting 20 structure which includes the pipe 23, in the relation shown. This may be done by forming the tube straight, inserting the crooked end portion 29 of the pipe 23 through the valve stem hole of said tube, screwing the 25 valve stem 31 into the member 30 on the extremity of the pipe 23, within the tube, and then splicing together the ends of the tube.

The tube 16 is then inserted in the lower 30 mold section 14, the plug 21 entering the socket 18^a, and the collar 24 and the pipe 23 fitting into the grooves provided therefor in the lower mold section and the block 17. The valve stem 31 is thus brought to and held in a tangential position at the middle 35 of the mold cavity. The upper mold section is then placed upon the lower, and the mold is placed in the press, being slid on the platen 10 until the socket makes a fluid-tight connection with the plug 35 by endwise 40 movement thereonto. The press is then closed upon the mold and steam is injected into the tube 16 through the hose 38, pipe 19, plug 21, valve-stem 31, and intermediate conduit-sections, to inflate the tube and press it out 45 against the mold, which is heated by platens 10, 11, the steam also heating the tube from the inside. The position of said valve stem is such that the steam jet does not impinge directly against a wall of the tube but circulates circumferentially or longitudinally, 50 of the tube, resulting in a substantially uniform heating of all parts of the latter. I do not, however, broadly claim this tangential injection feature.

55 The mold is then removed from the press and opened, the internal steam pressure being relieved by the parting of the conduit at the plug 35, or prior thereto in any known or preferred manner. The tube and the 60 steam-conducting structure connected therewith are then lifted from the lower mold section together, the valve stem is drawn into its final position in the wall of the tube by means of the pipe 23, and the latter is removed for use with the next tube.

My invention provides means for quickly connecting and disconnecting the mold, while in the press, with a source of steam supply, and the fluid-conduit section which enters the tube may be quickly assembled in 70 fluid-tight connection with the conduit section permanently mounted on the mold, and quickly detached therefrom.

As the collar 24 may be fitted snugly to the pipe 23, its molding face 25 surrounding 75 said pipe molds a smooth exterior surface, free from rands, fins or irregularities, about the valve stem hole of the tube, suitable for receiving the bead-spreader lug.

Details of construction may be modified 80 without departing from the scope of my invention, and I do not wholly limit my claims to the vulcanization of annular tubes.

I claim:

1. In vulcanizing apparatus the combination, with the upper and lower platens of a press, of a pipe-coupling member mounted on the lower platen, and a mold supported on the lower platen and having a complementary pipe-coupling member adapted 85 to connect with the first said member by a sliding movement of the mold.

2. Apparatus for vulcanizing annular tubes comprising an annular mold having a fluid conduit leading from its outer periphery to the inner side of the mold cavity, and a plug-and-socket fluid coupling for 95 said conduit at the outer periphery of the mold, one member of said coupling being secured to said mold.

3. Apparatus for vulcanizing annular tubes comprising an annular mold provided with a fluid conduit from its outer periphery to the inner side of the mold cavity, a terminal member for said conduit adapted 100 to support a valve-stem tangentially within said cavity, and a plug-and-socket fluid coupling member for said conduit fixed on the outer periphery of said mold.

4. Vulcanizing apparatus for hollow annular articles comprising an annular mold having a fluid conduit from its outer periphery to the inner side of its mold cavity, a plug-and-socket fluid coupling for said 110 conduit at the outer periphery of the mold, 115 one member of said coupling being secured to the mold, and an annular lip-packing for sealing said coupling.

5. Vulcanizing apparatus for hollow, annular articles comprising an annular mold 120 having a fluid conduit lying wholly within the vertical dimension of said mold and extending from its outer periphery to the inner side of the mold cavity, a plug-and-socket fluid-coupling element for said conduit fixed on the outer periphery of said mold, a press platen, and a plug-and-socket fluid-coupling member secured to said platen.

6. Vulcanizing apparatus for hollow, an-

5 nular articles comprising an annular mold having a fluid conduit lying wholly within the vertical dimension of said mold and extending from its outer periphery to the inner side of the mold cavity, a plug-and-socket fluid-coupling member for said conduit fixed on the outer periphery of said mold, a press platen, a plug-and-socket fluid-coupling member secured to said 10 platen, and a lip-packing adapted to form a seal between said coupling members.

6 7. Vulcanizing apparatus for hollow annular articles comprising complementary annular mold sections, one of said sections being provided with a fluid-conduit lying wholly within the vertical dimension of said section, extending from the outer periphery to the inner periphery of said section and there terminating in a plug-and-socket coupling element, and another plug-and-socket coupling element associated therewith and communicating with the cavity of the mold.

8. Vulcanizing apparatus for hollow, annular articles comprising complementary annular mold sections, one of said sections being provided with a fluid-conduit lying wholly within the vertical dimension of said section, extending from the outer periphery to the inner periphery of said section and there terminating in a coupling element, another coupling element associated therewith and communicating with the cavity of the mold, and a lip-packing adapted to form a seal between said coupling elements.

9. Vulcanizing apparatus for hollow articles comprising coacting mold sections, one of said sections being provided with a fluid passage opening onto its parting face, and means for conducting fluid from said passage into the mold cavity.

10. Vulcanizing apparatus for hollow articles comprising coacting mold sections, one of said sections being provided with a fluid passage terminating in a coupling element having a fixed position with respect to said section, and a fluid-conducting structure adapted to be held between said mold sections in communication with said coupling element and with the mold cavity.

11. Vulcanizing apparatus for hollow articles comprising coacting mold sections, one of said sections having a plug-and-socket fluid-coupling member in a fixed position thereon, and a fluid-conducting structure including a plug-and-socket member, said structure being adapted to be held between said sections in communication with the first said fluid-coupling member and with the mold cavity.

12. Vulcanizing apparatus for hollow articles comprising coacting mold sections and a fluid-conducting structure adapted to be held between said sections in communication with the mold cavity, said structure having an apertured part adapted to extend through

the wall of the article and having a molding surface surrounding said part for molding an exterior surface of the article.

13. Vulcanizing apparatus for hollow articles comprising coacting mold sections 70 and a structure adapted to be held between said sections with a part thereof extending through a wall of the article, said part being adapted to support a fitting within the article during vulcanization, and said structure having a molding surface surrounding said part for molding an exterior surface of the article.

14. Vulcanizing apparatus for hollow articles comprising coacting mold sections and 80 a fluid-conducting structure adapted to be held between said sections in communication with the mold cavity, said structure having an apertured, threaded part adapted to extend through a wall of the article, and having a molding surface surrounding said part for molding an exterior surface of the article.

15. Vulcanizing apparatus for hollow, annular articles comprising an annular mold section, a complementary annular mold section 90 provided with a fluid passage from its outer periphery terminating in a coupling element having a fixed position relative to said section, and a fluid-conducting structure adapted to be clamped between the mold sections in communication with said fluid passage and with the mold cavity.

16. Vulcanizing apparatus for hollow, annular articles comprising an annular mold section, a complementary annular mold section 100 provided with a fluid passage from its outer periphery terminating in a coupling element having a fixed position with respect to said section, and a fluid-conducting structure adapted to be clamped between the mold sections in communication with said fluid passage and with the mold cavity, said structure including an angular pipe adapted to extend into the mold cavity with its extremity in a substantially tangential position.

17. Vulcanizing apparatus for hollow, annular articles comprising a lower mold section, an upper mold section, a plug-and-socket fluid coupling member secured to one 115 of said mold sections, a complementary plug-and-socket fluid-coupling member, and an angular pipe communicating with and secured to the last said coupling member and adapted to be held between said mold members with one of its end portions lying tangentially within the mold cavity.

18. Vulcanizing apparatus for hollow, annular articles comprising an annular mold section, a complementary annular mold section 125 provided with a fluid passage from its outer periphery terminating in a coupling element having a fixed position with respect to said section, and a fluid-conducting structure adapted to be clamped between the mold

sections in communication with said fluid passage and with the mold cavity, said structure including an angular pipe adapted to extend into the mold cavity with its end 5 portion lying in a tangential position, said end portion being adapted to support a fitting within the article during vulcanization.

19. Vulcanizing apparatus for hollow, annular articles comprising an annular mold 10 section having a fluid-coupling element in a fixed position on the outer periphery of said section, a fluid coupling element having a fixed position with respect to said section, and fluid-conducting means lying wholly 15 within the vertical dimension of said mold

section and connecting said fluid-coupling elements.

20. Vulcanizing apparatus for hollow articles comprising coacting mold sections, one of said sections being formed with a recess 20 on its parting-face, and a fluid-conducting structure adapted to lie in said recess between said mold sections, said structure including a pipe adapted to extend through a wall of a hollow article contained in the 25 mold and a member having a molding surface surrounding said pipe.

In witness whereof I have hereunto set my hand this 11th day of February, 1922.

JOHN R. GAMMETER.
